UNITED STATES PATENT OFFICE.

CARLOS M. VELÁZQUEZ, OF CARÁCAS, VENEZUELA, ASSIGNOR TO CHARLES H. LOCKETT, OF BROOKLYN, NEW YORK.

DESIGN FOR AN INSULATOR-BRACKET.

SPECIFICATION forming part of Design No. 25,830, dated July 21, 1896.

Application filed April 1, 1896. Serial No. 585,825. Term of patent 14 years.

To all whom it may concern:

Be it known that I, CARLOS M. VELÁZQUEZ, a citizen of the Republic of Venezuela, and a resident of Caracas, Venezuela, have invented 5 a Design for Insulator-Brackets, of which the following is a specification.

The view in the accompanying drawing fully illustrates my design for an insulator-bracket for electrical conductors, this view 10 being an elevation or face view.

The bracket is stirrup-shaped, with two arms D D, substantially parallel to each other, while the outer lines at the bottom of the stirrup are in reverse curves d', terminating in

a reduced shoulder d², back of which is the 15 threaded stem E. On the inner face of the stirrup is a large curved notch d.

I claim—

The design for the insulator-bracket as shown and described. 20

In testimony whereof I have signed my name to this specification in the presence of two subscribing witnesses.

CARLOS M. VELÁZQUEZ.
